ARBOR FOR SPOOLS OR THE LIKE

George B. Markle, Jr., Hazleton, Pa.

Application April 20, 1940, Serial No. 330,793

5 Claims. (Cl. 242—134)

This invention relates to arbors for spools or the like, and is a companion application of my application filed of even date herewith, the object being to provide an arbor so constructed that two arbors can be employed for supporting a spool of any length.

Another object of my invention is to provide an arbor which is exceedingly simple and cheap in construction and yet durable in use.

Another object of my invention is to provide an arbor having a shoulder to form a stop, or a support for the spool to limit the inward movement of the arbor into the spool.

Other and novel features of the invention will be hereinafter set forth in the appended claims.

In the drawing—

Figure 1 is a side elevation of a pair of arbors partly in section arranged in a spool;

Figure 2 is a detail end view;

Figure 3 is a side elevation of a modification;

Figure 4 is a detail end view of the construction shown in Figure 3;

Figure 5 is a side elevation partly in section of another modified construction of arbor;

Figure 6 is an inside face view of the head shown in Figure 5.

In the embodiment of my invention, as shown in Figures 1 and 2, I employ a central metal core 1, preferably tubular in form, on which is welded adjacent one end a head 2 composed of a circular metal disc which is bent back upon itself, as shown at 3, and then outwardly to form an annular laterally projecting supporting flange 4 spaced from periphery of the head to form a stop shoulder 5 for the shell 6, as shown in dotted lines in Figure 1 in placing the shell in position on the arbor. The flange is herein shown formed continuous, but it can be formed of a plurality of sections, as shown in the embodiment of my invention, as shown in Figures 5 and 6, to form supporting surfaces for the free ends of the wire. In either construction, a lateral supporting surface is formed for connecting the ends of the wires to the head. While the head is shown spaced from the end of the core, it can be flush with the end of the core, as shown in another embodiment of my invention.

One end of the core is provided with cross slots 7 and 8, in which are arranged substantially U-shaped resilient wires 9 and 10, provided with bowed arm portions 9' and 10' extending towards the head, having their end portions extending through apertures 4' formed in the flange 4, the extreme ends being bent at right angles, as shown at 11, to secure the bowed wires in their proper

position therein. This provides a simple construction to frictionally support a shell or spool thereon by the resiliency of the bowed wires. The bowed wires present inclined surfaces to the inner wall of the shell in positioning a shell thereon to prevent the shell from being injured. The shoulder or stop 5 limits the inward movement of the arbor into the shell. It is of course understood that a single arbor could be used for supporting a shell in a vertical position.

In the embodiment of my invention, as shown in Figures 3 and 4, 12 indicates a tubular core having a head 13 secured thereon, constructed as disclosed in Figures 1 and 2. Arranged on the core are the open ring portions 14 formed in substantially U-shaped resilient wires 15 and 16, which are provided with bowed arms 15' and 16', having their free end portion extending through apertures formed in the flange 13' of the head, the extreme ends being bent at right angles, as shown at 17, for retaining the wires therein.

In the embodiment of my invention, as shown in Figures 5 and 6, 18 indicates a tubular core on which is secured a circular disc forming a head 19, the peripheral edge being bent back upon itself, as shown at 20, to strengthen the same. Punched inwardly from the face of the head are a plurality of sections 21, forming supporting surfaces which are apertured to receive the ends 20 of the wires 22, constructed as disclosed in Figures 3 and 4. As the wires have open ring portions they can be sprung apart to allow them to be placed in position or removed from the core and will be held in their proper position by the resiliency of the wires. The inner face of the head forms a stop for the shell to prevent the same from entering the shell too far. The central opening of the head is provided with an annular flange 23 to embrace the core. I wish it to be clearly understood that the construction of wires disclosed in Figures 1 and 2 can be used with the construction of head disclosed in Figures 5 and 6, without departing from the spirit of my invention.

Under certain conditions, it has been found that an arbor constructed, as disclosed in this application, can be used to an advantage in connection with the construction disclosed in my companion application 330,792, filed of even date herewith.

What I claim is:

1. An arbor for spools or the like comprising a core, a head secured on one end of said core, U-shaped wires carried by the other end of said core, said head being provided with apertured

lateral supporting surfaces spaced from the periphery of said head, the free ends of said wires being secured in the apertures of said supporting surfaces.

2. Supporting means for spools or the like comprising a pair of duplicate arbors adapted to be placed in the respective ends of a spool, each arbor comprising a core having a head at one end provided with lateral projecting supporting surfaces spaced from the periphery of said head, U-shaped resilient wires carried by the other end of said core having their free ends mounted in said supporting surfaces, and means formed on the ends of the wires for securing said wires in said supporting surfaces.

3. An arbor of the kind described comprising a core, a head secured on one end of said core provided with a lateral projecting apertured flange spaced from the periphery of said head,

U-shaped wires provided with open ring portion embracing said core having bowed arm portions extending through the apertures of said flange, the ends of the wires being bent at right angles to position and hold said wires in said flange.

4. An arbor for spools comprising a core having slots in one end thereof, a head secured on the other end of said core provided with lateral apertured extensions, U-shaped wires mounted in the slots of said core having bowed arms, the ends of said arms extending through the apertured extensions.

5. An arbor for spools comprising a core having a head at one end, and U-shaped wires at the other end, supporting surfaces carried by said head, the arms of said wires being connected to the supporting surfaces of said head.

GEORGE B. MARKLE, JR.
